UNITED STATES PATENT OFFICE.

HENRY D. LEFEVRE, OF BAY CITY, MICHIGAN.

COMBINED LETTER-SHEET AND ENVELOPE.

SPECIFICATION forming part of Letters Patent No. 372,685, dated November 8, 1887.

Application filed December 14, 1886. Serial No. 221,534. (No model.)

To all whom it may concern:

Be it known that I, HENRY D. LEFEVRE, a citizen of the United States, residing at Bay City, in the county of Bay and State of Michigan, have invented certain new and useful Improvements in Combined Letter-Sheets and Envelopes; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to improvements in combined letter-sheets and envelopes; and it consists, chiefly, in the construction and arrangement of the several parts, as I hereinafter more fully describe and claim; and the object 20 of my invention is to provide a combined letter-sheet and envelope that will present all the advantages of the security of the ordinary envelope and separate sheet, and also the advantage of being easier to fold and seal and to open 25 after sealing, besides requiring less material and labor to be used in its construction than in an ordinary separate sheet and envelope.

My invention is illustrated in the accompanying drawings, in which--
30 Figure 1 represents my improved letter-sheet and envelope folded for mailing. Fig. 2 is the same partly folded. Fig. 3 is the same open for writing. Fig. 4 shows the device folded for mailing without sealing. Fig. 5 is the same 35 partly folded. Fig. 6 is a modified form of Fig. 3. Fig. 7 shows the device in the form of an envelope for mailing matter without sealing.

Similar letters refer to similar parts throughout the several views.

a represents the top or head portion of the sheet, and upon the opposite side of which the address is to be written.

b is an extended portion of the top *a*, and 45 upon which the writing is to be placed. This sheet is divided with ruled lines *p*, in the usual manner, except at the proper point for folding, to indicate which the lines are broken or dotted, as *l m*, which are used in the writing 50 in the same manner as the solid lines, the space between each being the same. These dotted lines are arranged so that each outer portion

to be folded is one space narrower than the one nearer the head *a*, so that by folding the outer portion, *o*, at *l*, the edge of the part *o* reaches within one space of the line *m*, and, 55 folded again, reaches nearly to the line *n*, and is then folded upon the head portion *a*.

c is a flap extended from the upper edge of the head portion *a* opposite the sheet *b*, and is 60 folded at the dotted line *q* upon the part *a* and the already folded portion *b*, as shown in Fig. 2, and is provided with an opening, *f*, located in a position to be in the central portion of the part *a* when the flap *c* is folded. 65

d is a flap extending from one end of the portion *a*, and folds at the line *r* over and upon the part *c*, before folded upon the portions *a* and *b*, and is provided with an opening, *g*, which, when the flap is folded, opens directly 70 into the opening *f* and leaves a portion, *b'*, of the folded part *b*, beneath the openings, uncovered by the flaps *c* and *d*.

e is a flap extending from the head portion *a* and from the end opposite the flap *d*, and is 75 folded at the dotted line *s* upon the portions *b*, *c*, and *d*, already folded. The outer end of the flap *e* is provided with a circular piece, *h*, the diameter of which is slightly smaller than the openings *g* and *f*, so that the under side of 80 the part *h* being gummed and pressed into the openings *g* and *f*, it comes upon and adheres to the portion *b'*, which appears beneath the openings and securely seals the sheet in the form shown in Fig. 1. 85

t is a U-shaped cut made in the flap *e*, with the ends of the cut a short distance from the point of joining the flap *e* with the circular piece *h*, and forming the piece *i*, having a free end which remains as a portion of the flap *e* 90 until the letter is to be opened or unsealed. Then the sealed package is pushed or bent upward from beneath, slightly raising the free end of the piece *i*, which is then caught by the finger and thumb and torn away, as shown 95 by the dotted lines in Figs. 1 and 2. This leaves the letter-sheet free and clear of all sealing or fastening, and can in no way tend to injure the writing thereon.

The sheet and envelope may be folded and 100 secured, for sending printed matter by mail without sealing, by passing, after folding, the piece *h* through the openings *f* and *g*, and folding it back beneath the flap *e*, as shown by the

dotted lines in Figs. 4 and 5. This arrangement forms a complete and secure package, which may be opened for inspection by turning back to its original form the piece *h*, and 5 may be again secured without trouble or mutilation, and other matter may be inserted with and folded with the sheet in the same manner as with an ordinary envelope; and the package is opened by the receiver by tearing 10 away the piece *i*, as before described, which renders the operation of opening the envelope much quicker and easier than with the ordinary methods.

The envelope may be used separately, if desired, by reducing the length of the sheet *b* and placing it in the form of a flap, *u*.

For some uses the sheet may be perforated on the line *n* at the joining with the head portion *a*, so that the sheet may be easily torn 20 away from the head portion, and the sheet is then in proper form for filing away; or, if desired, the lines *q*, *r*, and *s* may be perforated, and flaps *c*, *d*, and *e* may then be torn off, which leaves the sheet and head portion in 25 proper form for filing away.

Having described my invention, what I claim as new, and desire to secure by Letters Patent, is—

1. In a combined letter-sheet and envelope, 30 the head portion *a* and the sheet portion *b*, extending from one side edge of the head portion, in combination with a flap, *c*, extending

from the opposite side edge of the head portion and provided with an opening, *f*, a flap, *d*, extending from one end of the head portion 35 and provided with an opening, *g*, and a flap, *e*, extending from the opposite end of the head portion and provided on its outer free end with a gummed portion, *h*, of a dimension less than the openings *f* and *g*, substantially 40 as and for the purpose set forth.

2. In a combined letter-sheet and envelope, the head portion *a*, the sheet *b*, connected with and folded upon the head portion, the flap *c*, connected with the opposite side edge of the 45 head portion and provided with the opening *f*, and folded upon the sheet *b*, the flap *d*, connected with one end of the portion *a*, and provided with an opening, *g*, and folded upon the flap *e*, and a flap, *e*, connected with the opposite end of the head portion and provided on its outer end with the gummed portion *h*, passed through the openings *f* and *g*, and secured to the folded sheet, in combination with a portion, *i*, of the flap *e*, partially cut out and 50 with its inner side adhering to the flap near the portion *h*, substantially as and for the purpose set forth.

In testimony whereof I affix my signature in presence of two witnesses.

HENRY D. LEFEVRE.
